FIG. 2.

UNITED STATES PATENT OFFICE

JOHN A. CARSON, OF HUNTINGTON, NEW YORK

ELECTRIC SWITCH

Application filed March 27, 1928. Serial No. 265,146.

This invention relates to electric switches, and more particularly to an electric switch for use with burglar alarms adapted to produce a visible or audible signal.

The primary object of the invention is to provide a simple, positively acting switch arranged to be automatically set to maintain a closed circuit, and to remain set until opened or turned off by means of a control key in the hands of an authorized person.

With these and other objects in view, the invention resides in certain novel construction and combination and arrangement of parts, the essential features of which are hereinafter fully described, are particularly pointed out in the appended claims, and are illustrated in the accompanying drawings, in which:—

Figure 1 is a horizontal sectional view through a burglar alarm casing showing the present switch;

Figure 2 is a vertical sectional view through the burglar alarm casing, looking toward one side of the latter;

Figure 3 is a sectional elevational view of the circuit control switches; and

Figure 4 is a diagrammatic view of certain electrical circuits incorporating the present improvements.

Referring to the drawings by reference characters, the numeral 10 designates a box-like burglar alarm housing hingedly mounted upon a panel 11 adapted to be mounted upon a wall or like supporting structure within reach of a person, as shown in Figure 1 of the drawings. The housing may be held closed by any suitable key controlled lock or the like (not shown) for preventing tampering with the parts contained therein, by unauthorized persons. Mounted on the inside of the front wall of the housing is a key controlled lock mechanism 13 which is accessible for operation from the outside by passing a key 14 through a key hole slot 15 in the housing. The lock mechanism 13 includes a slidable bolt 16 which is movable beyond opposite sides of the lock housing to respectively engage electric contact switches 17 and 18. The switches 17 and 18 are carried on the inside of the front wall of the

housing in a plane even with the sliding bolt 16. The switch 17 includes a stationary flat contact 19, while a flat spring contact 20 is mounted in spaced relation thereto and has a contact point for engagement with the contact 19 when the bolt 16 is moved to a retracted position. The free end of the contact 20 extends beyond the adjacent end of the contact 19 and is bent angularly as at 21 to provide bolt engaging portions.

The switch 18 includes a stationary flat contact 22 with which a flat spring contact 23 engages when the bolt 16 is extended into engagement with the angularly bent end 24. The normal tendency of the spring contact 23 is to move away from the contact 22.

Supported by the panel 10 is a shelf 25 for supporting a plurality of dry cells which constitute a battery 26 for supplying current to the several circuits for the burglar alarm.

Also supported on the panel 10 are relays 27 and 28. The relays include armatures 29 and 30 respectively for actuating spring tongues 31 and 32 to cause them to engage spring contacts 33 and 34. The relays 27 and 28 when energized serve to close certain circuits through the sets of contacts 31 and 33, and 32 and 34 which in reality constitute switches A and B.

In this instance the switch 17 is arranged in and controls what I shall term a "house circuit" C while the switch 18 is arranged in and constitutes an alarm circuit D. Arranged within the house circuit C is the battery 26, a wire 38 from which leads to the contact 19. A wire 39 leads from the other contact 20 of the switch 17 and is led around the windows and doors to be protected, the same being indicated by the numeral 40. The circuit is completed about the windows and doors by lining the same with foil as is the usual custom whereupon opening of a window or door will cause the breaking of the foil and consequently the breaking of the circuit C. The wire 39 leads to the coil of the relay 27, while a wire 41 from the relay is joined to a wire 42 which returns to the battery. This constitutes the house circuit and when the alarm device is set for operation, the authorized person turns the key 14 to a

position to cause the bolt 16 to move from the position shown in Figure 4 of the drawings to release the contact 20 to allow it to engage the contact 19 and engage the contact 23 to cause it to close the alarm circuit. When the switch 19 is closed, the current from the battery will flow through the relay 27 causing energizing of the armature to pull the contact 33 away from engagement with the contact 31 thus opening switch A which is part of the alarm circuit. A wire 43 leads from the contact 31 to the contact 22 of the switch 33 and connects with the wire 38 on one side of the battery 26. The other contact 23 of the switch 18 has a wire 45 connected therewith which is connected with the wire 42 on the side of the battery opposite to that to which the wire 44 leads. The contacts 32 and 34 of the switch B are respectively connected to the wires 43 and 44 by wires 46 and 47. A wire 48 leads from the relay or drop 28 to the wire 45 while a second wire 49 leads therefrom and which is a continuation of the wire 42 heretofore mentioned. The electric lamp 36 and electric bell 37 are tapped into the wires 42 and 45 for simultaneous operation when the circuit C is broken in a manner to be now explained.

It has already been explained that when the switch 17 is closed, the relay 27 causes the opening of the switch A whereas manual closing of the switch 18 causes the alarm circuit to be set for operation. The closing of the switch 18 does not affect the normal open position of the switch B which must be closed to close the entire alarm circuit through the bell, lamp, battery, and relay 28 which must be energized through the closing of the switch A.

Assume that an attempt has been made by a burglar to enter an establishment by forcing the opening of a window or door, which will cause the breaking of the foil and consequently the opening of the house circuit C. This causes deenergizing of the relay 27 which allows the contact 31 to spring into engagement with the contact 33 closing the circuit through wire 44 to battery 26, through wires 42, and 49 to relay 28, thence through wires 48, 45, switch 18, wire 43 to contact 31 which causes energizing of the relay 28, which attracts contact 32 to engage contact 34 which maintains the relay 28 in an energized position irrespective of whether the house circuit is again closed which would tend to open switch A. The bell and electric lamp being arranged in the same circuit as the relay 28 will operate so long as it is energized. To stop the alarm from sounding, it is necessary for the authorized person to insert the proper key 14 into the lock 13 and move the bolt 16 from engagement with the contact 24 of the switch 18 to break the alarm circuit.

When the device is in an unset position, the bolt 16 is in engagement with the con-

tact 20 of the switch 17 holding the same from engagement with the contact 19 whereupon both the house and alarm circuits are open and no current is passing therethrough, thus relieving strain on the battery when the device is not intended for operation. When set for operation the current is only passing through the primary or house circuit which requires but a small amount of current.

While I have described what I deem to be the most desirable embodiment of my invention, it is obvious that many of the details may be varied without in any way departing from the spirit of my invention, and I therefore do not limit myself to the exact details of construction herein set forth nor to anything less than the whole of my invention limited only by the appended claims.

What is claimed as new is:—

1. In an electrical burglar alarm device, a pair of switches, each of which includes a stationary contact and a spring contact, the spring contact of one switch tending to engage its co-acting stationary contact while the spring contact of the other switch tends to normally lie in spaced relation to its co-acting stationary contact, and key actuated mechanism movable into engagement with the respective spring contacts for actuating them against their spring tendencies.

2. In combination with a pair of electric switches, each switch including a stationary contact and a co-acting spring contact, the spring contact of one switch tending to engage its co-acting stationary contact while the spring contact of the other switch tends to normally lie in spaced relation to its co-acting stationary contact, a key actuated lock embodying a housing, and a bolt slideable beyond opposite ends of said housing for movement into alternate engagement with the respective movable contacts for actuating them against their spring tendencies substantially as and for the purpose described.

3. A switch of the class described comprising in combination with a lock having a slideable bolt, circuit wiring including a rigid terminal disposed in alignment and in substantial end facing spaced relation with said slideable bolt, a resilient terminal disposed in parallel relation with said first terminal and partly contacting therewith to provide a closed circuit, and an inclined end on said resilient terminal, said latter end disposed in the space between the opposed ends of said first terminal and said slideable bolt, whereby on sliding movement of said bolt its end is effective to contact with said inclined end for moving said inclined end laterally to flex said resilient contact and open the circuit.

In testimony whereof I have affix my signature.
